No. 689,874.

Patented Dec. 31, 1901.

F. HAGER.

BOOKBINDING SHEET.

(Application filed June 16, 1900.)

(No Model.)

Fig. 2

UNITED STATES PATENT OFFICE.

FREDERICK HAGER, OF PORTLAND, OREGON, ASSIGNOR, BY MESNE ASSIGNMENTS, TO PERFECTION BOOK-BACK CO., A CORPORATION OF NEW YORK.

BOOKBINDING-SHEET.

SPECIFICATION forming part of Letters Patent No. 689,874, dated December 31, 1901.

Application filed June 16, 1900. Serial No. 20,489. (No model.)

To all whom it may concern:

Be it known that I, FREDERICK HAGER, a citizen of the United States, and a resident of 547 Fourth street, Portland, county of Multnomah, and State of Oregon, have invented 5 certain new and useful Improvements in Bookbinding-Sheets, of which the following is a specification, reference being had to the accompanying drawings, forming a part thereof, 10 in which similar letters of reference indicate corresponding parts.

This invention relates to an improvement of Patent No. 651,351, which was granted to me on the 12th day of June, 1900, for an improvement in book-backing of the class employed in the art of bookbinding for backing and assembling the several signatures comprising a book-body.

The improvement embodies a strip-sheet 20 and a flexible base; and the object thereof is to provide an efficient article of this character in which the plurality of strips embodying the strip-sheet are all connected to each other in parallel alinement.

25 The improvement will be hereinafter fully described, and specifically set forth in the annexed claims.

In the accompanying drawings, forming part of this specification, Figure 1 is a face or 30 plan view of a back embodying my improvements, and Fig. 2 is a detail transverse sectional view taken on the line 2-2 of Fig. 1.

In the bookbinder's art these backs have been formed by pasting separate strips of 35 cardboard upon a flexible base or fabric, said strips being arranged in pairs, with their adjoining edges abutting, and the respective pairs being parallel and separated by a narrow intervening space; but this method of 40 pasting the separate strips upon the flexible base or fabric is exceedingly tedious and slow and a perfect parallel alinement of the pairs of strips is virtually impossible. The variation in the width of the separating-spaces between the respective pairs of strips makes the 45 back irregular and precludes its perfect operation when applied in position in the binding of the book. It is the purpose of my present improvement to entirely obviate the above 50 disadvantages and to produce a back in which

the pairs of strips embodied in an integral sheet will be in perfect and accurate alinement, so that the maximum degree of efficiency and operation is secured and the time necessary in an effort to aline the severed 55 strips is saved.

Referring to the drawings, A designates the flexible base or sheet, which may be of fabric or any other suitable or desired material.

B designates the strips of cardboard or 60 analogous material which are pasted upon the flexible base. These strips are produced by approved machinery in a series of pairs 65 b b, having their meeting edges abutting and connected to each other by integral bridges embodying the unsevered portions of material m, whereby a plurality of pairs are connected to each other to provide a sheet of desired width, said pairs being in perfectly parallel relative position and separated by the 70 narrow intervening spaces b'; but the strips of the respective pairs are connected by narrow integral necks n, extending across the intervening spaces b'. In practice the series of strips as just above described are provided upon their backs with mucilage or 75 other suitable adhesive substance by which they may be pasted upon the flexible base A, and it will be understood that the narrow integral connecting-necks n and bridges m 80 will retain the strips in permanent connection and parallel alinement until they are secured to the flexible base, thus avoiding all guesswork, loss of time, and the use of the eye in securing a parallel alinement of the strips. 85

Another important feature of my improvements is that the adhesive substance is applied to and carried upon the back of the connecting-strips, so that only that part of the flexible base which is covered by the strips 90 receives any of the adhesive substance, while in the practice heretofore pursued in the art in the operation of pasting single strips one by one upon the flexible base the adhesive substance was first applied to the whole surface of the flexible base and the strips were set upon said adhesive surface, which operation was not only uncleanly, but the adhesive substance also caused the flexible base to shrink and become stiff and hard. 95

The operation and advantages of my invention will be readily understood by those skilled in the art to which it appertains. The several signatures comprising the book-body 5 are respectively sewed to the flexible base A by means of threads which pass through the said base into the space b'. The strips are then folded upon each other in accordion plaits to bring the several signatures together and 10 form the book-body. The integral narrow connecting-necks n will not interfere to any degree whatever with the flexibility secured by the intervening spaces b' when my improved backing is applied in position, and 15 after the strips are secured upon the flexible base and the backing is in position the dividing cut line l between the respective strips of each pair which forms the abutting edges of each strip will open up freely and the 20 bridges m will be readily fractured, while the exact uniform size of the spaces b' will insure a true and perfect operation.

I do not confine myself to the specific details of mechanical construction as herein 25 shown and described, as it is obvious that under the scope of my invention I am entitled to structural variations.

Having thus described my invention, what I claim as a new and useful improvement of 30 the invention described and claimed in my Patent No. 651,351, and desire to secure by Letters Patent, is—

1. As a new article of manufacture, an integral strip-sheet for backing and assembling 35 book-signatures, embodying a plurality of pairs of strips, adjacent members of two pairs being connected by bridges, and the members of each pair being in parallel position with a uniform intervening space bridged by integral narrow connecting-necks extending between them, substantially as shown and described.

2. As a new article of manufacture, an in-

tegral strip-sheet for backing and assembling book-signatures, embodying pairs of strips, 45 adjacent members of two pairs having their meeting edges abutting and bridged by uncut parts, and the members of each pair being in parallel position and separated by a uniform intervening space and bridged by integral narrow connecting-necks extending between the strips of the respective pairs, substantially as shown and described.

3. As an improved article of manufacture, an integral strip-sheet for backing and assembling book-signatures, embodying pairs of strips in parallel position, adjacent members of two pairs being connected by bridges, and the members of each pair being separated by a uniform intervening space bridged by integral narrow connecting-necks, said strip-sheet being provided with and carrying upon its back an adhesive substance, whereby it may be applied to a flexible base, substantially as shown and described. 65

4. As an improved bookbinding-sheet for assembling book-signatures, the combination, with a flexible base, or fabric, of an integral strip-sheet embodying pairs of strips adjacent members of two pairs having their abutting edges connected by integral bridges and placed in parallel position, the members of each pair being separated by a uniform intervening space bridged by integral narrow connecting-necks, and an adhesive agent attaching said strip-sheet to the flexible base, substantially as shown and described. 70

In testimony that I claim the foregoing as my invention I have signed my name, in presence of two witnesses, this 28th day of May, 80 1900.

FREDERICK HAGER.
